UNITED STATES PATENT OFFICE

BERNARD PHILLIPS, OF NEW YORK, N. Y.

CLOTHES WASHING DEVICE

Application filed October 7, 1931. Serial No. 567,480.

This invention relates to clothes washing devices commonly known as clothes pounders, and the invention comprises an elongated handle having affixed to one end, a circular metallic member to which is secured a cylindrical piece of fabric having secured to one end a perforated metallic disk for the passage of water. The invention further comprises a coil spring mounted within the cylindrical piece of fabric for normally holding the perforated metallic disk in an extended position.

The primary object of this invention, is to provide a device of the above mentioned character which will compress upon force applied to the handle to create a suction within the cylindrical fabric member upon continued reciprocation of the handle.

A still further object of this invention, is to provide a device of the above mentioned character which will function to draw dirt and other foreign matter out of clothes being washed by continuously reciprocating the handle of the device when the perforated metallic disk is in contact with the clothes.

Other objects and advantages of the invention, will become apparent during the course of the following description, forming a part of this specification and in which,

Figure 1 is a top elevation of the invention showing the circular configuration of the top metallic disk and illustrating the guard extending therefrom;

Figure 2 is a bottom elevation of the device, illustrating the perforated bottom metallic disk and showing the manner in which the water guard is extended over the diametrical cross-section of the device;

Figure 3 is a side elevation of the invention illustrating the manner in which the cylindrical fabric member is secured to the top metallic disk and the bottom perforated metallic disk;

Figure 4 is a vertical cross-sectional view illustrating the structural details of the device;

Figure 5 is a side elevation of the device, showing the same compressed and illustrating the manner in which the cylindrical

fabric member is collapsed during its operation; and

Figure 6 is a fragmentary enlarged cross-sectional view, illustrating a detail of construction of the connection between the cylindrical fabric member and the top metallic disk.

In the drawing, wherein for the purpose of illustrating the invention and wherein like reference characters will be employed to designate like parts throughout the same, the reference character 5 will generally be employed to designate a circular metallic disk partially cup-shaped and having an angular inturned portion 6 continuing outwardly in a flared manner terminating in a beaded rim portion 7. Secured to the circular metallic disk 5 is a handle receiving socket 8 having an annular flange 9 rigidly secured to the metallic disk 5. A handle 10 may be secured in the handle socket 8 and held therein by screws as at 11.

Secured to the circular metallic member 5 is a cylindrical fabric member 12 having one end thereof overturned as at 13 for forming a pocket for receiving an annular split ring 14. The annular ring 14 and overturned portion 13 of the cylindrical fabric are adapted to be received in the annular recess formed by the inturned portion 6 of the metallic disk member 5. If desired, the ring 14 may be split so that it can be depressed for removing the fabric 12 from the head 5.

Removably secured to the outer end of the cylindrical fabric 12 is a metallic perforated disk 15 which is also cup-shaped and is provided with side walls 16 terminating in a beaded portion 17 over which the fabric 12 may be placed and held in position by a circular tying element or the like. It has been found in practice that the beaded portion 17 is sufficient for holding the metallic disk 15 to the lower open end of the fabric member 12. As clearly illustrated in Figures 2 and 4, the cup-shaped metallic disk member 15 is provided with a series of openings 18 for the passage of water when the device is used for washing clothes.

Mounted within the cylindrical fabric member 12 is a helical coil spring 20 having

one of its free ends engaging the upper metallic disk member 5 while the opposite end engages the cup-shaped perforated metallic member 15 to normally hold the same in extended relation relative to the disk member 5.

It will be noted that the skirt portion 21 of the inverted cup-shaped metallic member 5 is flared outwardly from the inturned annular portion 6 to produce a guard member which will prevent water from passing upwardly into the direction of the user. The annular flared portion 21 also forms a guide for the fabric cylindrical member 12.

15 In operation, the operator merely grasps the handle 10 and reciprocates the same causing the cup-shaped disk member 15 to engage the clothes and causing the collapsing of the cylindrical fabric member 12. Expansion of 20 the spring and chamber produces a suction within the chamber which suction is utilized to withdraw dirt and other foreign matter from the clothes through the opening 18 in the cup-shaped disk member 15.

25 It is to be understood, that the form of the invention herewith shown and described is to be taken as a preferred embodiment of the same and that various changes in the shape, size and arrangement of parts may be resorted to without departing from the spirit of the invention as defined by the scope of the subjoined claims.

I claim:-

35 1. A clothes pounder of the character described, comprising a metallic disk member, said metallic disk member having an interior annular recess, a handle secured to the metallic disk member, a cylindrical fabric member having one end secured in the annular 40 recessed portion, a cup-shaped member having a plurality of openings in the bottom thereof secured to the opposite end of the cylindrical fabric member, and a coil spring mounted within the cylindrical fabric member, having its ends bearing against the metallic disk member and the metallic cup-shaped member.

50 2. A clothes pounder of the character described, comprising a metallic disk member having an annular internal recess portion, an outwardly flared annular extension extending from the annular recess portion, a handle secured to the metallic disk-shaped member, a cylindrical fabric member having one end 55 thereof overturned for receiving a clamping ring, said clamping ring and overturned edge being adapted to be received within the annular recess portion, a perforated cup-shaped metallic member secured to the opposite end 60 of the cylindrical fabric member, and a coil spring mounted within the cylindrical fabric member for holding the perforated cup-shaped metallic member in an extended position relative to the disk-shaped metallic member.

3. A clothes pounder of the character described, comprising a metallic disk member, a handle secured to the metallic disk member, an annular extension formed on the metallic disk member extending downwardly and outwardly, a cylindrical fabric member having one end secured to the metallic member, a perforated cup-shaped metallic member secured to the opposite end of the cylindrical fabric member, and a coil spring mounted within the cylindrical fabric member for holding the cup-shaped perforated member in an extended relation relative to the disk-shaped metallic member.

4. A clothes pounder of the character described, comprising a metallic disk-shaped member arcuately curved in cross-section, an annular recessed portion formed in the disk-shaped member, said annular recessed portion terminating in an outwardly flared annular portion, a handle secured to the disk-shaped member, a cylindrical fabric member having one end held within the recessed portion of the disk-shaped member, a perforated cup-shaped metallic member secured to the opposite end of the cylindrical fabric member, and a coil spring mounted within the cylindrical fabric member, having one end bearing against the disk-shaped metallic member and the other end engaging the cup-shaped metallic member.

5. A clothes pounder of the character described, comprising a metallic disk-shaped member arcuately curved in cross-section, an annular recessed portion formed at the edge of the arcuately curved metallic disk member, an annular outwardly and downwardly flared portion secured to the recessed portion, a handle secured to the metallic disk-shaped member, a cylindrical fabric member having one of its open ends secured within the annular recessed portion of the metallic disk-shaped member, a perforated cup-shaped metallic member secured to the opposite open end of the cylindrical fabric member, and a coil spring mounted within the cylindrical fabric member having one end engaging the metallic disk-shaped member and the opposite end engaging the metallic cup-shaped perforated member.

In testimony whereof I affix my signature.

BERNARD PHILLIPS.
